LIQUEFIED GAS DISPENSING APPARATUS

William C. Buttner, Winnetka, Ill., assignor to
The Bastian-Blessing Co., Chicago, Ill., a cor-
poration of Illinois

Application June 25, 1941, Serial No. 399,715

15 Claims. (Cl. 62—1)

1
The present invention relates generally to liquefied petroleum gas dispensing systems and more particularly to the type of installation in which the storage tank is buried underground where heat present in the ground assists in vaporizing the gas.

The present invention is a continuation in part of application Serial No. 359,002, filed by me September 30, 1940, for Gas dispensing apparatus and now abandoned.

In many respects, the apparatus employed to represent the present invention, is similar to that shown in the William C. Buttner application Serial No. 271,089 filed May 1, 1939, reference to which is hereby made. To the extent that a similarity of parts exists between the embodiments of the two inventions, the disclosure of the above application is incorporated herein for a better understanding of the present invention.

The petroleum product employed in the systems with which the present invention is concerned, is preferably of the paraffin series, such as butane or propane, or both, and this fuel is stored in the form of a liquefied gas.

In order to use the fuel in an appliance such as a gas stove, the liquefied gas is vaporized and vaporization may be accomplished in one of two ways which are essentially similar.

One of these ways is the so-called "batch" system, in which vaporization is carried on in the tank and the vaporized fuel is progressively withdrawn for service from the top of the tank. The second, or so-called "flash" system; the liquefied gas is withdrawn from the bottom of the tank and conducted through a pressure regulator where a sudden reduction in pressure causes the fuel to flash into gas.

In the batch system, the heat absorption due to vaporization is largely confined to the tank, whereas in the flash system, the refrigeration effect is concentrated or localized with respect to the region of the pressure regulator. In the former case, the fuel is mostly gas when it reaches the reduction regulator and comparatively little refrigeration is involved outside of the tank except that involved in revaporization, whereas, with the flash system, a great deal of heat absorption is required in a small space.

In fact, in the flash system, it has been found that when large quantities of gas are being withdrawn through a flash regulator, sufficient absorption takes place that in the event the regulator is in direct contact with the earth fill, the moisture in the earth adjacent to the regulator, is frozen to form an ice cap which hinders the

transfer of heat from the earth to the regulator. In brief, with such an installation, the regulator creates a secondary frost line and a condition which, like a frosted coil in a refrigerator, defeats the purpose of bringing the regulator into contact with the earth and hinders the needed transfer of heat.

Although the present invention will improve vaporization for both systems, it is illustrated in its preferred form in combination with the flash system where the conditions are found to be more severe. However, certain relations are discussed which will enable one skilled in the art to adapt the invention to batch systems. Consequently, it is one of the objects of the present invention to improve heat transfer conditions in the vaporization phase of a liquefied petroleum gas system.

A further object of the invention is to provide a vaporizing system for liquefied petroleum gas dispensers wherein the vaporization regulator as well as the service conduit, is supplied with heat drawn from a surface area of earth greatly in excess of the surface area within which the heat is absorbed. It is another object of the invention to locate a vaporization regulator in the earth, below the frost line, and remove it from contact with the earth by providing an air space so disposed that moisture condensation collecting upon the regulator will run off into the ground remote from the air space and further humidity acquired from the ground assists, along with convection in transferring ground heat to the regulator.

Moreover, it is one of the objects of the invention to have the vaporization regulator in heat transfer contact with the wall of a container having an anti-freezing fluid therein exposed to ground heat, which prevents excessive frosting of the regulator under heavy or sudden flows of gas in the service conduit and serves to defrost the regulator rapidly at periods of time when the flow of fluid is less active.

More specifically, it is one of the objects of the invention to locate the vaporization regulator in heat exchange contact with the wall of the storage tank for the purpose stated so that the gas inside of the tank can condense upon the wall of the tank proximate to the regulator to discharge heat thereto and will then drip back into the liquid to absorb more heat which has been accumulated from the ground by the body of liquid through the wall of the tank.

It is also a purpose of the invention to minimize the amount of service conduit disposed outside the tank as regards that portion of service

conduit disposed between the vaporization regulator and the point where it connects with a coil disposed in the storage tank.

These being among the objects of the present invention, other objects will become apparent from the drawing, the description relating thereto and the appended claims.

In the drawing:

Fig. 1 is a side elevation partly in section illustrating the invention in its preferred embodiment.

Fig. 2 is a fragmentary enlarged section taken upon the line 2-2 in Fig. 1.

Fig. 3 is an enlarged section taken upon line 3-3 of Fig. 2.

As has already been mentioned, the invention is illustrated in connection with the flash system in which liquefied gas is first withdrawn from the storage tank having pressures normally experienced with liquefied petroleum gas; is passed through a first vaporizing regulator which reduces the pressure to a first stage pressure range as low as practical and then is conducted through a second pressure regulator which reduces the gas pressure to the service pressure of 6 ounces per square inch.

In the drawing, a storage tank is indicated at 11, as buried in the earth 12 below the frost line 13 normally expected in the region where the installation is made. The tank is filled and vented through a standpipe 14 which carries a slip tube gauge 15 accessible at the cap 16 and a vent or vapor return pipe 17 provided with a splash deflector 18 at the lower end thereof.

The top of the standpipe 14 is sealed by a unitary manifold head 21 having a pressure gauge 22, fill port 23, vapor return port 24, and a safety valve 25 built integrally therewith. The head 21 is disposed in a concrete vault 26 buried below the surface of the earth 27 shielded with burlap if desired, and covered by a reinforced concrete cap 28 secured in place against tampering, as by bolts 29. The liquefied gas 31 is withdrawn from the bottom of the tank by a dip tube 32 provided with an excess flow check valve 33 therein to prevent escape of the fuel from the tank in the event there is a break in the system outside of the tank. A manually controlled shutoff safety valve is connected to an automatic pressure regulator or pressure reduction valve 35 by nipples 36 and a union 37.

The regulator 35 comprises a body portion 42 having an inlet 78 and outlet 79 therein with the inlet leading through a bridge 80 to a port 81 and the outlet leading from a valve chamber 82. The chamber is closed by a diaphragm 83 held in place by a bonnet 84 as flexed inwardly by means of a compression spring 85 mounted between a diaphragm plate 86 upon the diaphragm and an adjusting screw 87 threaded into the bonnet to establish a predetermined pressure upon a screw. A locknut 88 prevents inadvertent loosening of the screw 87.

The diaphragm plate has a threaded opening therein to fasten a yoke 89 upon the diaphragm which yoke straddles the bridge 80 and carries on the bottom end thereof a valve member 90 supporting a seat 91 in cooperation with the port 81.

A back cap 41 extending downwardly from the valve body forms the bottom wall of the chamber and is in heat exchange contact not only with the body portion 42 but also with the valve member 90 where a cylindrical boss 92 guides a center piece 93 upon the valve member. A back

cap spring 94 is employed to stabilize the action of the valve and diaphragm.

The back cap 41 is flattened at its lowest extremity to contact the top of the container 11 in heat exchange relationship.

A platform 43, which, if made of metal, may be welded to the tank 11 as at 44, has an aperture 45 therein to receive the back cap 41 and permit that portion of the regulator to contact the tank in heat exchange relationship. The apertured platform serves to support the regulator against damage in transit and also serves as a heat conveying fin on the tank which radiates conducted heat after the tank is installed.

10 Vaporized gas is conducted from the regulator 35 by tubing 46 connected to the outlet side thereof, and the tubing 46 leads directly back into the tank as at 47 in sealed communication with a coil 48 which is disposed in the tank with a major portion of its length submerged in the liquefied gas 31.

15 The regulator 35, the valve 34 and connections 36 and 46 are covered by a box or housing 51 which rests on top of the tank 11 and has a hinged or removable cover 52. A pipe 53 filled with insulating material 54 connects the housing 51 with the concrete box 26 through an opening in the concrete box, and has disposed therein a valve shaft 55 operating the hand valve 34 as controlled by a handle 56 disposed in the box 26.

20 Other than for the slight infiltration that might take place through the heat insulating material 54, the stand-pipe 14 and regulator 35 are air and heat sealed from each other as by the filling 25 of earth between them. With this construction, the regulator 35 and connections conducting the liquefied gas and vaporized gas outside of the tank are sealed from access of freely moving atmosphere by a layer of removable earth filling, 30 yet the valve 34 in the housing 51 can be controlled without need for the removal of the earth filling which seals the housing 51 from the atmosphere.

25 The outlet end of the coil 48, indicated at 57 is preferably spaced from the inlet 47 of the coil as separated by earth, and, although shown as disposed at the center of the head 58 of the tank, may be located at any point convenient upon the tank.

30 A service main 61 leads from the outlet 57 into the cellar 62 or space below the first floor 63 of a dwelling. The main 61 when necessary, passes through the foundation 64 at an opening such as that indicated at 65 where it is sealed against the passage of moisture by an annular member 66 preferably made of a workable dense material which can be packed in place.

35 From the main 61, which preferably slopes towards the tank, the gas is carried upwardly by a riser 67 which connects with a finned vaporizer 68 of a type such as that disclosed in the Patent #1,752,166 issued to R. G. Ford, March 25, 1930.

40 At the outlet of the vaporizer 68, a hand operated shutoff valve 71 is mounted on a bracket 72 which supports a shelf 73 on which is disposed a pressure reduction regulator 74 connected to the hand valve 71 by a tube 75. The pressure regulator 74 reduces the vaporized gas to the service pressure of 6 ounces per square inch and the gas is then delivered to an appliance (not shown) by the appliance conduit 76.

45 In the present invention the vent tube 79 for the regulator 74 is inclined downwardly throughout its length to drain from the regulator any moisture collecting therein. In the particular ar-

5

arrangement shown, the regulator 14 is disposed above the outlet 18 of the vent tube and also above the space into which the outlet opens whether it be a glycerin cup such as shown in the co-pending Buttner application, Serial No. 271,089, another source of anti-freeze fluid, or a confined spaced where humidity is kept at a minimum.

In operation, once the tank 11 has been filled to the permitted level, in the well known manner, the heat present in the earth becomes effective to raise the temperature of the liquefied gas to its boiling point by which sufficient vapor is generated to establish a pressure head in the tank.

The valve 34 is opened and liquefied gas will be forced through the regulator by the head pressure in the tank and the pressure of the withdrawn gas is reduced by the regulator to a low pressure.

With this reduction in pressure, the boiling point of the liquefied gas is suddenly lowered and the liquefied gas flashes into vapor to the extent that vaporization is supported by heat units available in the conducting parts that are necessary to sustain the temperature of the vapor above the condensation point at that pressure.

Thus, the regulator 35 and conduit 46 beyond the regulator becomes a refrigerated agent requiring a large quantity of heat to sustain the vapor phase of the fuel gas. The area of these parts is relatively small and therefore the heat absorption exerted at these points is very high. However, with the tank in contact with the relatively warm earth over a large area and the contact between the regulator 35 and the tank, this provides for direct heat conduction of large quantities of heat to the regulator. Furthermore, the housing 51 being in contact with the earth over a large area and the encompassed air which circulates convectively between the walls of the housing and the surface of the regulator, also supplies heat to relieve the refrigeration conditions.

The contact between the regulator and the tank renders the heat in the wall of the tank available to the regulator at the back cap to which any liquid unvaporized gravitates. Transfer of heat from the tank to the regulator in this area creates a cold zone at the top of tank onto which vaporized gas in the tank condenses to discharge heat to the cold zone and then drops back into the liquid to be heated and vaporized again, conduction and convection, both, taking place inside the tank for the accomplishment of this purpose.

With regard to the heat transfer in the housing 51, humidity in the air in the housing 51 condenses on the regulator to supply it with heat and the condensate runs onto the warm tank where it is evaporated again and again to repeat the convective and condensation-evaporation cycle. In these ways, the first stage regulator is able to effect vaporization to the maximum degree and maintains same for the normal flow or less than normal flow, experienced in the use of the gas.

Under the extra heavy flow of gas, the coil 48 in the tank assists in the initial vaporization, and where extreme outside cold might induce condensation in the service line, revaporization is had in the coil through the relatively abundant supply of heat available in the liquefied gas.

In this connection, with the tube 61 slanting towards the tank 11, any condensation sufficient

6

to provide a trickle in the service main will flow back into the coil for the revaporization mentioned provided the heat of the ground around the service main is insufficient for the purpose.

The finned vaporizer 68 assists in revaporizing when disposed where a warm fluid may contact it. Consequently, by maintaining the fuel in the service conduit vaporized by the means already described, the further reduction in pressure taking place in the second regulator further lowers the point of vaporization and assures a full flow of dry gas to the appliance.

In view of the fact that the second regulator breathes, the pressure control side of the diaphragm therein is vented to the atmosphere by the tube 79. The breathing action has a tendency to cause the collection of moisture in the tube and if it were possible for the moisture to reach the diaphragm compartment, it might freeze there and upset the functioning of the system by locking the diaphragm and the valve controlled thereby. This would constitute a dangerous condition.

The vent tube 79 in the present invention is inclined downwardly so that moisture at all times drains therefrom to prevent the collection of water condensate and in certain instances, where it may be found desirable to submerge the outlet 18 of the vent tube in an anti-freeze fluid or a dry space, the shape and construction of the tube 79 further assures the freedom of the regulator from any freeze-ups.

In this way, the present invention provides an improved liquefied gas dispensing apparatus and although in some respects it is difficult to account fully for the improved results which are obtained by the method and apparatus of the present invention, it is to be understood that any attempt to analyze the theories which are believed to be responsible for the improved and new results, is to be construed not as defining a mode of operation, but merely as a possible explanation of certain physical phenomena which have been observed.

Consequently, although a certain preferred embodiment of the present invention has been shown and described herein, a way has also been suggested by which the present invention may be utilized in the so-called "batch" systems and it will be apparent to those skilled in the art that various and further uses, modifications and changes may be made without departing from the spirit or substance of the invention, the scope of which is commensurate with the appended claims.

What is claimed is:

1. In a liquefied petroleum gas dispensing system having a storage tank buried below the frost line, a service conduit leading from the tank to an appliance, a pressure reducing valve in said conduit in contact with the tank, vault means providing an air space around the regulator sealed from the atmosphere by a wall of earth, means for filling the tank remote from the regulator, and a coil in said conduit between the regulator and appliance and disposed inside the tank.

2. In a liquefied petroleum gas dispensing system having a storage tank buried underground in heat exchanging relation with the surrounding earth and adapted to be filled from above the ground level, a delivery conduit communicating with the tank and extending to a point of use; a pressure reducing regulator in said delivery conduit arranged with the back cap thereof in contact with the tank to absorb some heat there-

from; and filler material between the regulator and the ground level to prevent atmospheric air from freely circulating in contact with and to permit access to the regulator only when the filler material is removed.

3. In a liquefied petroleum gas dispensing system having a storage tank buried underground in heat exchanging relation with the surrounding earth and adapted to be filled from above the ground level, a service conduit communicating with the tank at a point spaced from the point of filling by earth fill and extending to a point of use, a pressure reducing regulator in said conduit arranged in contact with the tank to absorb heat therefrom, means supporting earth around the regulator to provide a space containing a fluid between the regulator and the earth, and filler material between said means and the ground level to prevent atmospheric air from freely circulating in contact to the regulator.

4. In a liquefied petroleum gas dispensing system having a subterranean storage tank receiving heat from the earth and adapted to be filled from above the ground, a service conduit leading from the tank to a point of use, a pressure reducing regulator in said conduit disposed in contact with the tank, a housing around said regulator providing a space containing convectively circulated fluid between the regulator and the adjacent earth, and filler material between said housing and the ground level to prevent atmospheric air from freely circulating in contact with and to permit access to the regulator only when the filler material is removed.

5. In a liquefied petroleum gas system having a subterranean storage tank receiving heat from the ground and adapted to be filled from above the ground, a delivery conduit communicating with the tank and extending to a point of use, said conduit comprising a dip tube whose inlet is near the bottom of the tank for removing liquid from the tank, a pressure reducing regulator in contact with the tank and receiving liquid from said tube, and means including a filler material between the regulator and the ground level to prevent atmospheric air from circulating in contact with the regulator, said regulator being accessible when said means is removed.

6. In a liquefied petroleum gas system having a subterranean storage tank receiving heat from the ground, a delivery conduit communicating with the tank and extending to a point of use, and comprising a dip tube for withdrawing fuel from the tank in its liquid phase, a pressure reducing regulator in contact with the tank, and a second pressure regulator reducing the gas to a usable pressure at said point of use.

7. In a liquefied petroleum gas system having a subterranean storage tank receiving heat from the ground, a delivery conduit communicating with the tank and extending to a point of use, said conduit comprising a dip tube opening near the bottom of the tank for removing liquid from the tank, a pressure reducing regulator in contact with the tank, a coil disposed in heat exchange relationship with the contents of said tank and a second pressure regulator reducing the gas to a usable pressure at said point of use.

8. In a liquefied petroleum gas system having a subterranean tank receiving heat from the ground, a service conduit for vaporizing a liquefied petroleum gas comprising a dip tube opening near the bottom of the tank for withdrawing liquid from a body of liquid under pressure, a pressure reducing regulator in contact with said tank, a

second pressure regulator reducing the gas to a usable pressure at a point of use, a cover enclosing the first regulator to prevent atmospheric air from circulating in contact with the first regulator, said first regulator being accessible when the cover is removed.

9. In a liquefied petroleum gas system having a subterranean tank receiving heat from the ground, a service conduit for vaporizing a liquid petroleum gas comprising a tube for withdrawing liquid from a body of liquid under pressure at a point near the bottom of the tank, a pressure reducing regulator in contact with the tank, a vaporizer disposed in heat exchange relationship with the contents of said tank, a second pressure regulator reducing the gas to a usable pressure at a point of use; means including a filler material between the first regulator and the ground level to prevent atmospheric air from circulating in contact with the first regulator, said first regulator being accessible when said means is removed.

10. In a liquefied petroleum gas system having a subterranean tank receiving heat from the ground, a service conduit for vaporizing a liquefied petroleum gas comprising a tube opening near the bottom of the tank for withdrawing liquid from a body of liquid fuel under pressure, a pressure reducing regulator in contact with said tank, a second pressure regulator reducing the gas to a usable pressure at a point of use, a housing over the first regulator providing a space between the first regulator and the earth and filler material between the housing and the ground level to prevent atmospheric air circulating in contact with the first regulator being accessible when the filler material is removed.

11. In a liquefied petroleum gas system having a subterranean tank receiving heat from the ground, a service conduit for vaporizing a liquefied petroleum gas comprising means for educting liquid from a body of liquid fuel under pressure, a pressure reducing regulator in heat conducting contact with said tank, a vaporizer disposed in heat exchange relationship with the contents of said tank, a second pressure regulator reducing the gas to a usable pressure at a point of use; a housing over the first regulator providing a space between the first regulator and the earth, and filler material between the housing and the ground level to prevent atmospheric air circulating in contact with the housing, said first regulator being accessible when the filler material is removed.

12. In a liquefied petroleum gas dispensing system having a tank buried underground in heat exchange relationship with the surrounding earth, a conduit for vaporizing a liquefied petroleum gas comprising an inlet receiving fuel under pressure, a pressure reducing regulator having a body portion and a protruding portion thereon in heat receiving contact with the tank, a platform associated with the tank and having a hole therein for receiving said protuberance, said platform being disposed proximate the body portion of the regulator.

13. In a liquefied petroleum gas dispensing system having a storage tank buried below the frost line, a service conduit leading from the tank to an appliance, a pressure reducing device including a back cap defining approximately the lowest point of a compartment in the device, said back cap being in contact with the wall of said tank at a point removed from contact with atmospheric air, means for filling the tank remote from the pressure reducing device.

14. In a liquefied petroleum gas dispensing system, a container having a vaporizable liquid therein, a pressure reducing valve having a body with a chamber therein extending into the lowest portion of the body, a member upon the container to locate said lowest portion in contact with a wall of the container, means for conducting fuel to the valve under pressure, and means for conveying fuel from the valve to a point of use.

15. In a liquefied petroleum gas dispensing system having a storage tank buried underground in heat exchanging relation with the surrounding earth, a filler pipe extending from the tank to a point adjacent to the ground level, a delivery conduit communicating with the tank and extending to a point of use; a pressure reducing regulator in said delivery conduit arranged in direct contact with the tank to absorb some heat therefrom; and earth fill between the regulator and the ground level to prevent atmospheric air from

freely circulating in contact with and to permit access to the regulator only when the filler material is removed.
